(57) **CLAIM**

The ornamental design for a fuel cell metering valve, as shown and described.

DESCRIPTION

FIG. 1 is a top front perspective view of a fuel cell metering valve showing our new design.

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the Figures are included for the purpose of illustrating portions of the fuel cell metering valve and form no part of the claimed design.

1 Claim, 7 Drawing Sheets
